UNITED STATES PATENT OFFICE.

AMASA WORTHINGTON, OF BROOKLYN, NEW YORK.

STEAM-BOILER.

SPECIFICATION forming part of Letters Patent No. 429,164, dated June 3, 1890.

Application filed March 8, 1889. Serial No. 302,581. (No model.)

To all whom it may concern:

Be it known that I, AMASA WORTHINGTON, a citizen of the United States, residing at Brooklyn, in the county of Kings and State of New York, have invented certain new and useful Improvements in Steam-Boilers, of which the following is a specification.

My improvements relate to that class in which inclined tubes extend through the furnace, said tubes having vertical end connections or headers, and a horizontal separating-chamber placed above and united to them in such a way that the water mingled with steam may freely rise through the tubes and front connections and the water descend in like manner at the back; and the objects of my improvements are, first, to provide a boiler in which the tubes are connected in single vertical rows and having straight and independent outlets to the separating and mud drums; second, to make the headers of cylindrical form and have them so arranged that they will allow the tubes to lie in a staggered position; third, to facilitate handling and transportation by making the units or sections as small as is consistent with complete vertical rows of tubes; fourth, to promote free circulation, and, fifth, a boiler having large water capacity.

To these ends my invention consists of a header constructed of an integral tubular piece having expanded portions to receive series of tubes in a common vertical line, and contracted portions which fit alternate expanded portions of similar adjacent headers; and my invention also provides for a sectional flame-plate of a marginal character corresponding to that of the headers.

Referring to the accompanying drawings, Figure 1 is a side and Fig. 2 an end elevation, the brick-work being removed. Fig. 3 is a vertical longitudinal section through one of the heads and mud-drum. Fig. 4 is an end elevation of a number of the heads, showing two of them partly in section. Figs. 5 and 6 are views of the flame-plates, showing how they are applied and clamped to the tubes. Fig. 7 shows a modification in the shape of the heads. Fig. 8 shows two and Fig. 9 three heads cast together, and the bottom end of each shows how one larger pipe may be used for a connection instead of smaller pipes for each one, as shown at the opposite or top end

of the heads. Fig. 10 is a section on line X X, Fig. 9.

Similar letters refer to similar parts throughout the several views.

I overcome these objections in the manner shown, reference being had to the drawings, Fig. 1. S is the separating-drum, having two nozzles *n* on the top for taking off steam and attaching the safety-valve, man-hole *m* in one end, and two flanged cross-pipes *s*, having openings in which to expand the tubes.

The headers H unite the inclined tubes T in vertical rows or sections, each header receiving one tube from each alternate horizontal row of tubes. Thus the height is made up of double sections, each single section as placed in the boiler standing above or below the adjoining section one-half the distance between its tubes. I contract the sides of the heads 2 2, Fig. 4, so as to bring the tubes into a staggered position relative to one another. I make these headers, preferably, of cast-steel, malleable or wrought iron, and with caps *n* opposite the tubes. The flame-walls *f* are made of cast-iron plates, in halves, so as to fit around the tubes, and with fastenings at the top and bottom, so that they may be easily moved up or down along the tubes at any time. The front side is made hollow to hold some protecting material, such as fire-clay. I unite the sections with the separating-chamber S and the mud-drum M by tubes *t*, of smaller diameter than the inclined tubes T. This allows sufficient metal in the cross-pipes between the tubes and at the ends of the headers to expand against; also, permits free passage for the escaping gases through the downtakes in the rear.

The feed-water is supplied to the boiler through the separating-drum and the water-level carried at about the center of the same. The mud-drum M is fitted with a hand-hole for cleaning and blow-off. (Not shown.) The doors C C C are set in the inclosing brick-work and permit access for examination, cleaning, &c. The register-cleaning doors *r* are for the introduction of a nozzle for blowing the dust from the outside of the tubes.

I may support the boiler in any well-known way, such as by girders extending across the top carrying suspension-bolts attached to the drum; or the rear may rest upon the mud

drum and the forward end on the front in any suitable manner.

Having thus described my invention, what I claim, and desire to secure by Letters Patent, is—

1. In a water-tube boiler, a header constructed of an integral tubular piece having expanded portions to receive series of tubes lying in a common vertical plane, and having contracted portions between such expanded portions to fit alternately-located expanded portions of similar adjacent headers.

2. The combination, with the headers H, adapted to secure one tube in each alternate horizontal row of inclined tubes and fitted to lie in close order alternately at a higher and

lower level, of the tubes T, small tubes t, separating-chamber S, and mud-drum M, as and for the purpose specified.

3. In a water-tube boiler, a flame-plate constructed in vertically-divided half-sections, having when combined expanded portions which embrace series of tubes lying in a common vertical plane, and contracted portions between such expanded portions to fit alternately-located expanded portions of similar adjacent flame-plates.

AMASA WORTHINGTON.
